US0D1071659S

(12) **United States Design Patent** (10) **Patent No.:** **US D1,071,659 S**
(45) **Date of Patent:** **** Apr. 22, 2025**

(54) **FOOD INDUSTRY EXTRUSION MACHINE COMPONENT**

(71) Applicant: **Source Technology ApS**, Kolding (DK)

(72) Inventors: **Kim Doctor Krintel**, Kolding (DK);
Brian Fabricius Hjorth, Vejle (DK)

(73) Assignee: **SOURCE TECHNOLOGY APS**,
Kolding (DK)

(**) Term: **15 Years**

(21) Appl. No.: **35/516,488**

(22) Filed: **Jan. 9, 2023**

(80) **Hague Agreement Data**

Int. Filing Date: **Jan. 9, 2023**

Int. Reg. No.: **DM/226924**

Int. Reg. Date: **Jan. 9, 2023**

Int. Reg. Pub. Date: **Mar. 3, 2023**

(30) **Foreign Application Priority Data**

Jul. 7, 2022 (EM) 009078264-0001

(57) **CLAIM**

The ornamental design for a food industry extrusion machine component as shown and described.

DESCRIPTION

1. Food industry extrusion machine component

1.1 : Perspective

1.2 : Front

1.3 : Back

1.4 : Right

1.5 : Left

1.6 : Top

1.7 : Bottom

1. Fig. 1.1 shows a perspective view of the design; Fig. 1.2 shows a front view of the design; Fig. 1.3 shows a back view of the design; Fig. 1.4 shows a right side view of the design; Fig. 1.5 shows a left side view of the design; Fig. 1.6 shows a top view of the design; Fig. 1.7 shows a bottom view of the design; The dash-dash broken lines shown in drawing 1.3 show portions that form no part of the claimed design. The dot-dash broken lines show a boundary of the claim and form no part of the claimed design.
